FIG. 3.

INVENTOR
NORMAN DELL
By *At the time of filing*

UNITED STATES PATENT OFFICE.

NORMAN DELL, OF BUFFALO, NEW YORK.

WATER-OPERATED POWER-GENERATING DEVICE.

Application filed September 28, 1925. Serial No. 59,192.

My invention relates to improvements in devices for harnessing the kinetic energy of swiftly moving currents of water and the object of the invention is to erect a track carrying structure over the flow upon which are mounted a plurality of cars having downwardly extending vanes which project into the flow and thus carry the cars along the track in the direction in which the water is flowing, such cars being adapted to connect with an endless belt or other power conducting means for transforming their longitudinal movement into a rotative movement which is coupled to dynamos or actuates any required machinery. A further object of my invention is to swingably mount vanes upon the cars so that when they are being immersed and removed from the water flow at either end of the structure they will be turned parallel to the direction of the stream thus offering practically no resistance to the flow of water and reducing the strain upon the respective hoisting and lowering means to a minimum. A still further object of the invention is to provide an upper inclined track upon which the cars are adapted to run downwardly from the rear to the forward end of the structure where they are again dropped into their working position to be carried to the rear end of the structure by the flow of water therebeneath.

My invention consists of the above device as set forth all as hereinafter more particularly described and illustrated in the accompanying drawing in which:

Fig. 1 is a side elevational view of my complete structure showing it positioned above a stream of water which is traveling in the direction indicated by the arrow.

Fig. 2 is an enlarged cross sectional view through the lower tracks showing one of the cars mounted thereon also the endless chain to which the cars connect when traveling along such track, and

Fig. 3 is a fragmentary plan view of the forward portion of one of the cars and a portion of the track upon which it is mounted, the means being shown for swinging the vanes from their actuating or stream engaging position into the position wherein they afford the least obstruction to the flow of water thus permitting them to be readily lifted in and out of the stream.

Like characters of reference indicate corresponding parts in the different views.

1 is a canal or river bed through which flows a volume of water in the direction indicated by the arrow and 2 and 3 are a pair of steel structural towers adapted to either bridge the stream or be positioned therein. 4 is a horizontal track extending between the lower portions of the two towers being parallel with and running in the same direction as the flow of water and positioned just above its surface. A pair of hoist platforms 5 and 6 are positioned in the respective towers 2 and 3 and are provided with sections of track 7 which join with the respective ends of the track 4 when such platforms are in the lowermost position. 8 are the hoist mechanisms which may be electrically or otherwise actuated for hoisting the platforms. Extending between the towers and positioned above the track 4 a second track 9 is provided; this track is inclined downwardly from the rear tower 3 to the front tower 2, the sections of track 7 upon the hoisting platforms 5 and 6 being adapted to join with the respective ends of such track 9 when such platform hoists are in their uppermost positions.

A plurality of cars 10 having running wheels 11 are provided upon the device and are adapted to run upon the tracks 4 and 9 as will be hereinafter described. 12 are a plurality of downwardly extending vertical vanes provided upon the under side of each car being centrally mounted upon upwardly extending shafts 13 which extend upwardly through the center of the cars and through the centrally positioned bosses 14 on their upper faces. 15 are collars secured upon the upper ends of the shafts 13 by means of pins 16 or any other suitable means.

17 is a tangentially extending lug upon the collar 15 being in a parallel plane to the plane of the respective vane 12 therebeneath and 18 is a stop projecting outwardly and downwardly from one of the structural struts 19 of the tower 3 and adapted to push the lug 17 from the position illustrated in dotted lines in Figure 3 into the position illustrated in full lines in such figure as the car passes beneath the strut 19 thus swinging the respective vane 12 from its water flow engaging position into a non-engaging position.

20 are a pair of endless chains running from one tower to the other and positioned upon either side of the track 4. 21 are upwardly extending lugs upon the cars 10 and 5 are adapted to engage lugs 22 upon the chain 20 when the cars are travelling along the track 4 and thus move the chain with the consequent rotation of the chain sprocket 23 which in turn is suitably connected to a 10 driving wheel 24 which connects with dynamos or any other desired machinery.

It is to be understood of course that my device has to be of very rigid construction and that the tracks 4 and 9 will be suitably 15 mounted upon open web girders 25 and 26, an upper girder 27 extending between the upper ends of the towers to insure that they will stay in correct alignment, one with the other.

29 The operation of my device is as follows: One of the cars 10 moves onto the hoist platform 5 which is lowered either by the weight of such car or by mechanical means until the platform comes into the same level 25 as the track 4 the ends of the track 7 thereon connecting with such track 4. As the vanes 12 of the car are now immersed in the stream it will be seen that the car will be carried forward by the flow of water, the lug 21 thereon coming in contact with one of the 30 lugs 22 upon the chain 20 and as the car travels along the track 4 under the impetus of the flow of water the chain 20 will be moved with the consequent rotation of the 35 driving wheel 24 as before described. When such car reaches the end of the track 4 it will run onto the section of track 7 upon the platform 6, the vanes being turned into their 40 inoperative position by means of the stop 18 coming in contact with the lugs 17 which connect with the vane supporting shafts 13 as before described. It will be readily understood that when the vanes are turned into this position an enormous pressure will be 45 removed from the car and from the platform 6 upon which it is positioned thus preventing unnecessary strains upon the whole rear end of the structure. The hoist platform 6 now moves upwardly to a level with the track 9 from where the car runs downwardly upon such track to the platform 5 in the tower 2 which has now returned to 50 its uppermost position. The platform 5 now descends as before described, the car going through the same operation. For swinging the vanes 12 back into their water flow engaging position any suitable means may be used in the tower 2, for example a similar 55 stop to the stop 18 in the tower 3, engaging the lug 17 and swinging it back into its original position.

It will be seen from the drawings that I have not confined myself to the use of one car in my device it being quite practical to 60 use a plurality of cars depending in num-

ber upon the distance between the towers 1 and 2, it also being understood that should the distance be sufficiently great supplemental towers would have to be erected at intervals to support the tracks. From the above description it will be seen that I have devised a very simply constructed water power harnessing device in which the water engaging vanes will practically extend from the surface of the water to the bed of the stream and thus utilize a very large percentage of the flow of water.

What I claim as my invention is:—

1. A device of the class described, comprising a track positioned above and extending in the same direction as a flow of water, cars on the track having vanes thereon extending into the water and adapted to propel the cars along the track under the influence of the water flow, means for lifting the cars so that the vanes are removed from the water at the down-stream end of the track and gravity means for returning the cars to the beginning or up-stream end of the track.

2. A device of the class described, comprising a track positioned above and running in the same direction as a water flow, cars mounted upon the track and having vanes thereon and extending into the water for propelling the cars along the track under the influence of the water flow, means for elevating the cars when they reach the down-stream end of the track, and an inclined track positioned above the aforesaid track to which the cars are elevated and upon which they run downwardly to the beginning or up-stream end of the track.

3. A device of the class described, comprising a track positioned above and running in the same direction as the water flow, cars mounted upon the track and having pivotally mounted vanes thereon and extending into the water for propelling the cars along the track under the influence of the water flow and means at the down stream end of the track for partially rotating the vanes about their pivot for moving them from a substantially transverse water engaging position to a substantially longitudinal position to lessen their obstruction to the water.

4. A device of the class described, comprising a track positioned above and running in the same direction as the water flow, cars mounted upon the track, means for elevating the cars at the down stream end of the track, pivotally mounted vanes extending downwardly from the cars and adapted to project into the water for propelling the cars along the track under the influence of the water flow, means at the down stream end of the track for partially rotating the vanes to move them from a substantially transverse water engaging position to a substantially 130 longitudinal position.

longitudinal position to lessen their obstruction to the water, and means whereby the vanes are lifted out of the water in their transverse position when the cars are elevated at the down stream end of the track.

5. A device of the class described, comprising a track positioned above and running in the same direction as the water flow, cars mounted upon the track and having pivotally mounted vanes thereon extending into the water for propelling the cars along the track under the influence of the water flow, means for elevating the cars when they reach the down stream end of the track, an inclined track positioned above the aforesaid track to which the cars are elevated and upon which they run downwardly to the beginning or upstream end of the track, means at the down stream end of the track for partially rotating the vanes to move them from a substantially transverse water engaging position to a substantially longitudinal position to lessen their obstruction to the water, and means whereby the vanes are lifted out of the water in their transverse position when the cars are elevated at the down stream end of the track.

6. A device of the class described, comprising a pair of spaced apart towers positioned in the water flow, a track positioned above the water and extending between the towers in the same direction as the water flow, cars on the track having vanes thereon extending into the water and adapted to propel the cars along the track under the influence of the water flow, means in the tower at the down stream end of the track for elevating the cars when they reach said tower, an inclined track positioned above the afore-

said track and extending between the towers 40 and to which the cars are elevated when they reach said tower and upon which they run downwardly to the tower in the upstream end of the track, and means in said tower for lowering the cars to the firstmentioned track wherein the vanes upon the cars again engage the water flow.

7. A device of the class described, comprising a pair of spaced apart towers positioned in the water flow, a track positioned 50 above the water and extending between the towers in the same direction as the water flow, cars on the track having vanes pivotally mounted thereon extending into the water and adapted to propel the cars along the 55 track under the influence of the water flow, means in the tower at the down stream end of the track for elevating the cars when they reach said tower, means at the down stream end of the track for partially rotating the 60 vanes to move them from a substantially transverse water engaging position to a substantially longitudinal position to lessen their obstruction to the water, and means whereby the vanes are lifted out of the 65 water in their transverse position when the cars are elevated at the down stream end of the track, an inclined track positioned above the aforesaid track and extending between the towers and to which the 70 cars are elevated when they reach said tower and upon which they run downwardly to the tower in the up stream end of the track, and means in said tower for lowering the cars to the firstmentioned track wherein the 75 vanes upon the cars again engage the water flow.
